UNITED STATES PATENT OFFICE.

MARK A. MACOMBER, OF PERRY, NEW YORK.

PAPER-BAG HOLDER.

No. 925,363.

Specification of Letters Patent.

Patented June 15, 1909.

Application filed October 12, 1908. Serial No. 457,398.

To all whom it may concern:

Be it known that I, MARK A. MACOMBER, a citizen of the United States, residing at Perry, in the county of Wyoming and State 5 of New York, have invented or discovered certain new and useful Improvements in Paper-Bag Holders, of which the following is a specification, reference being had thereto in the accompanying drawings.

10 This invention relates to a device for use in grocery stores and the like, for holding paper bags adapted to contain various articles, and has for its object to provide a paper bag holder which may be conveniently mounted beneath the counter, so that it may 15 be swung about to bring into convenient position the various receptacles containing the paper bags of different sizes which the holder is adapted to contain.

20 In the accompanying drawings, Figure 1 is a plan view, partly broken out, showing one form of the improved bag holder in position beneath the counter. Fig. 2 is a side view of the same, with the counter in vertical section. Fig. 3 is a detail view to illustrate the operation of the spring or friction fastening-device. Fig. 4 is a detail section on line 4—4, Fig. 1, showing a preferred form of bag-holding cell or compartment. 25 Fig. 5 is a plan view illustrating another form of the invention, and Fig. 6 is a side view of the form of invention shown in Fig. 5.

Referring to the drawings, 12 denotes a 30 portion of a counter such as is in common use in stores, and 13 denotes a semi-circular receptacle attached to the under side of the counter by means of a pivot-bolt 14 which is in turn supported by a plate 15 screwed 35 or otherwise attached to the underside of the counter. The receptacle 13 is provided with a series of cells or compartments of different sizes adapted to contain different sized bags, which compartments or receptacles can be readily exposed, for access thereto, by swinging the said receptacle outward, to the position indicated in dotted lines in 40 Fig. 1, on the pivot-bolt 14.

To retain the swinging receptacle 13 in 45 place beneath the counter, when not in use, so that it will not be accidentally displaced, and thereby get in the way of the attendant, a spring-holding device for the same is preferably provided. The form of spring-holding device, shown most clearly in Fig. 2, 50 comprises a bent wire 16 the outer end of

which is attached to the lower end of the pivot bolt 14 by a nut 17, and the inner end of which is turned upward at substantially a right angle and is provided with a loop 18 60 encircling a stud or screw 19 in the under side of the counter and between the head of which and the said loop 18 is interposed a spiral spring 20 which serves to lift the inner end of said wire. A washer 21 is 65 preferably interposed between the top of said spring 20 and the said loop 18. To the underside of the bottom of the swinging receptacle is attached a rib 22 preferably inclined or curved upward toward the bottom 70 of the said receptacle at both ends and provided at or near its center with a notch 23 which, when the receptacle is in position beneath the counter, will receive the wire 16 so as to retain the said receptacle in place. 75 The edges of the said notch are inclined, as shown, so that when a slight force is applied to the receptacle 13 the wire 16 will be forced downward, permitting the said receptacle to swing on its pivot, and when 80 the receptacle is returned to place in either direction the inclined or rounded under surface of the rib 22 will ride over the said wire and force it downward until the notch 23 arrives over the wire, when the latter will 85 immediately spring upward and hold the receptacle in place.

Any or all of the compartments or cells of the receptacle 13 may be constructed as shown in the detail view Fig. 4, in which 24 90 denotes a piece of tin plate or other suitable sheet metal bent into a curved shape and secured to the inner end of the compartment in which it is placed in such a manner as to form a curved end wall therefor. Paper 95 bags, such as are intended to be placed in the various compartments of the holder or receptacle, are usually folded in such a manner that their bottoms are much thicker than their tops, and when a package of bags 100 of greater length than the receptacle is forced into one of the compartments provided with the curved inner or end wall the upper ends of the bags will be inserted first and will be curved upward, as indicated in 105 dotted lines in Fig. 4, and thus the receptacle will be adapted to hold a large number of such bags the outer or lower ends of which, being thicker than the upper or inner ends, will fill the outer end of the receptacle. 110

Instead of forming the receptacle semi-circular, as shown in Figs. 1 and 2, the bag-

holding receptacle may be made round, as shown in Figs. 5 and 6. When made in this form the pivoted receptacle, attached to the counter 12 by the pivot bolt 14, will preferably comprise upper and lower disks 25 between which are a number of partitions dividing the receptacle into wedge-shaped compartments opening to the edge of the receptacle, and into which compartments bags 10 may be inserted edgewise. As the bottoms of the bags are thicker than the tops thereof of course the bags will be placed in the receptacle with their top ends inward, and the wedge-shaped compartments 27, which are 15 of different sizes, will thus accommodate a large number of bags of different sizes, as will be understood. With this form of the invention a frictional spring-holding device, such as the curved plate spring 26, bearing 20 against one of the disks of the receptacle, will preferably be provided, so that the receptacle will be retained in any position to which it may be moved by the attendant.

From the foregoing it will be understood

that the invention provides a convenient paper bag holder which is rotatably or pivotally mounted beneath the store counter, and which is convenient of access when it is desired to take therefrom a paper bag of any size which may be wanted. 25 30

Having thus described my invention I claim and desire to secure by Letters Patent:—

The combination with a counter, of a paper bag holder pivotally mounted beneath the top of said counter and provided on its under side with a rib having rounded or inclined surfaces and a central notch, and a spring-actuated retaining device arranged to engage said notch when said receptacle 35 40 is swung inward beneath the counter.

In testimony whereof I affix my signature, in presence of two witnesses.

MARK A. MACOMBER.
